(57) **CLAIM**

The ornamental design for a Zuugie ball game board, as shown and described.

DESCRIPTION

FIG. 1 is front perspective view of a Zuugie ball game board showing my new design;

FIG. 2 is a front elevation view of the Zuugie ball game board of FIG. 1;

FIG. 3 is a rear elevation view of the Zuugie ball game board of FIG. 1;

FIG. 4 is a left side elevation view of the Zuugie ball game board of FIG. 1;

FIG. 5 is a right side elevation view of the Zuugie ball game board of FIG. 1;

FIG. 6 is a top plan view of the Zuugie ball game board of FIG. 1;

FIG. 7 is a bottom plan view of the Zuugie ball game board of FIG. 1;

FIG. 8 is a right-side sectional view of the Zuugie ball game board of FIG. 1, taken along line 8-8 of FIG. 3;

FIG. 9 is a back perspective view of the Zuugie ball game board of FIG. 1, shown with a pivotable support leg and pivotable leg lock bracket in an unfolded and locked position; and,

FIG. 10 is a back perspective view of the Zuugie ball game board of FIG. 1, shown with the pivotable support leg and pivotable leg lock bracket in a folded position.

The features shown in broken lines in the drawing depict portions of the design that form no part of the claimed design.

1 Claim, 8 Drawing Sheets
